UNITED STATES PATENT OFFICE.

FRANK YOKEL, OF AVALON, PENNSYLVANIA, ASSIGNOR TO PITTSBURGH LAMP, BRASS & GLASS COMPANY, OF PITTSBURGH, PENNSYLVANIA, A CORPORATION OF NEW JERSEY.

GLOBE HOLDER FOR ILLUMINATING FIXTURES.

Application filed June 21, 1923. Serial No. 646,795.

To all whom it may concern:

Be it known that I, FRANK YOKEL, a citizen of the United States, residing at Avalon, in the county of Allegheny and State 5 of Pennsylvania, have invented certain new and useful Improvements in Globe Holders for Illuminating Fixtures, of which the following is a specification.

This invention relates to an improved 10 globe or shade holding means for illuminating fixtures.

The invention has for its principal objects to provide a globe or shade clamping means of simple construction designed to 15 effectually hold a shade or globe in place and readily operable into and out of globe engaging position, the device being neat appearing and cheaply constructed.

The invention is particularly useful for 20 use in connection with the large globes of ceiling lights, although in no way confined to such use.

The invention may be readily understood 25 by reference to the accompanying drawings in which:

Fig. 1 is a side elevation of the shade or globe holder embodying my invention, showing a globe therein, part of the globe being broken away;

Fig. 2 is a vertical section through the globe holder, showing the globe in place;

Fig. 3 is a similar view, with the globe removed;

Fig. 4 is a detail view of one of the 30 globe engaging members; and

Fig. 5 is a detail view, showing the operating means for one of the globe engaging members.

In the drawings, A designates the globe 40 or shade holder, B is an ornamental canopy that may be interposed between the globe holder and the ceiling, and C designates the globe or shade.

The shade holder comprises an integral 45 sheet metal body or shell, spun or otherwise worked into shape, having a flat top portion 6, an outward curved part 7, a short vertical part 8, and a second outwardly curved part 9, the curvature of the latter 50 part being convex, while that of the upper or first curved part is concaved. The lower end of this hollow or shell body is open, to permit of the insertion and removal of the upper end of an illuminating

globe or shade. The contour of the interior of the shell conforms to its exterior. In the flat top 6 is an opening 10 through which may pass the end of a pipe or other conduit 11 (as shown in Fig. 2) to support 55 the shell.

Secured to the interior of the shell are a plurality, preferably two, globe engaging members 12 and 13 respectively. Member 12 comprises an integral body having arms 14 conforming to the inner curvature 60 of the shell and secured to the shell by pins 15 passed therethrough.

Formed on the body is a shoulder 14^a adapted to come against vertical part 8 of the shell, and below this the body is curved 70 or hook-shaped to receive the bead *a* of the globe C, the end part 16 of the body being adapted to project into the restricted neck portion *a'* of the globe. The member 12 is also arcuately curved in a horizontal plane, 75 in order to engage the circular bead *a* of the globe at all points of contact therewith.

Member 13, diametrically opposite member 12, is similar to member 12 to the extent described, and similar reference numerals have been applied thereto. In order, however, that the hook portion of member 13, which like that of member 12 is out of contact with the curved part 9 of the shell, 80 be less resilient than the hook portion of member 12, the pins 15 are disposed nearer the body of member 13, instead of being located at the ends of the arms 14.

Member 12 is provided with a vertical 85 slot 17. Threaded in a bushing on the shell 90 is a screw or bolt 18 having a knob 19, by means of which it may be turned. The inner end of this screw is reduced at 20 to pass through slot 12, and on the inner end 95 of the screw is a washer 21. By this arrangement, the inner end of the screw may turn in the slot and slide therein, but, as the screw is turned, it moves in or out, imparting a similar movement to member 12.

In use, the screw is turned to retract the 100 clamping member 12 until the bead of the globe or shade is inserted. Then the screw is turned in the opposite direction, and edge 16 is forced into the restricted neck *a'*, at 105 the same time that the entire globe is shifted laterally, so that the corresponding edge 16 of member 13 engages in the neck. When the screw has been turned sufficiently

to take up all play between the globe and clamping members, it should be turned no further. A lock nut 22 on the screw between the knob and the bushing may then be turned to secure the parts in this position.

The construction herein described is extremely simple, both in construction and operation. The shell entirely houses the clamping means, so that the only visible part thereof is the one operating screw and knob.

Various details in the arrangement and construction of parts are within the contemplation of my invention.

15 While I have shown the bushing 23 internally threaded to cooperate with the threaded bolt 18, it is within the scope of my invention to form the threaded portion in a wall of the shell or to otherwise provide a 20 threaded portion carried by the shell to co-act with the threaded bolt.

I claim as my invention:

1. A globe holding device comprising a hollow shell open at its lower end for the 25 reception of the top of a globe, a plurality of inwardly turned hook-like globe engaging members on the interior of the shell, and a screw passing through only one of said members and the shell by means of which the globe engaging member may be moved into and out of globe engaging position, said other member being substantially fixed in position.

2. A globe holding device comprising a hollow shell open at its lower end for the 35 reception of the top of a globe, a globe engaging member having a free hook-like globe engaging lower end portion and an upper portion which is secured to the interior of the shell, a screw engaging said member and passing through the shell by means of which the hook-like portion may be moved into and out of globe engaging position, and other fixed non-adjustable globe engaging 45 means within the shell for cooperation with said first globe engaging member.

3. A globe holding device comprising a hollow shell open at its lower end for the 50 reception of the top of a globe, a globe engaging member having a free hook-like globe engaging lower end portion and an

upper portion which is secured to the interior of the shell, said member having a vertically disposed slot therein, a screw having one end rotatably and slidably retained in the slot, said screw passing through the shell and having a threaded support therein, means on the outer end of the screw for turning it whereby to effect a movement of the hook portion into and out of relatively fixed non-adjustable globe engaging position, and other globe engaging means within the shell for cooperation with said first globe engaging member.

4. A globe holding device comprising a hollow shell, open at its lower end for the reception of the top of a globe, a pair of globe engaging members secured within the shell having relatively wide arcuate curved hook-shaped globe engaging parts spaced inwardly from the shell, the two members being opposite each other, and a screw connecting with only one member and passing through the shell by means of which said member may be adjusted toward and away from the other member, the two members being sufficiently wide to provide ample holding and supporting means for the globe.

5. A globe holder comprising a hollow bell-shaped shell open at its lower end and having an inwardly curved upper portion and an outwardly curved lower portion, with a substantially vertical portion between the inwardly and outwardly curved portions, correspondingly shaped resilient globe supporting devices secured at their upper ends in the shell and having their vertical part falling along the vertical part of the shell and having their outwardly curved part received in the outwardly curved part of the shell but spaced inwardly from said outwardly curved portion, said vertical parts on the globe supporting members and the shell limiting the outward spread of the supporting members, and a screw for effecting the lateral movement of only one of said supporting members, said other members being substantially fixed in globe engaging position.

In testimony whereof I affix my signature.

FRANK YOKEL.
